UNITED STATES PATENT OFFICE.

THOMAS O. HOPKINS AND SIDNEY H. EASTERDAY, OF KANSAS CITY, MISSOURI; SAID EASTERDAY ASSIGNOR TO SAID HOPKINS.

SCISSORS SHARPENER.

Application filed February 18, 1924. Serial No. 693,550.

To all whom it may concern:

Be it known that we, THOMAS O. HOPKINS and SIDNEY H. EASTERDAY, citizens of the United States, residing at Kansas City, in the county of Jackson and State of Missouri, have invented certain new and useful Improvements in Scissors Sharpeners, of which the following is a specification.

Our invention relates to scissors sharpeners and our object is to provide a simple, inexpensive and efficient device of this character by means of which scissors may be conveniently supported while being sharpened.

A further object is to provide means for supporting a whet-stone, file, or other instrument at the proper angle or inclination with relation to the holder for the purpose of giving the desired bevel to the cutting edges of the scissors.

Other objects will hereinafter appear and in order that the invention may be fully understood, reference will now be had to the accompanying drawing, in which:

Fig. 1 is a plan view of the device with a pair of scissors secured in position thereon to be sharpened.

Fig. 2 is a cross section on line II—II of Fig. 1.

Fig. 3 is a broken longitudinal section on line III—III of Fig. 1.

In carrying out the invention we employ a bed-plate 2, provided at its rear margin with an upturned gage 4 having an inclined surface 6 for holding each blade of the scissors A at the proper angle while being sharpened.

The forward portion of the bed-plate 2 is provided with a pair of upwardly extending bearings 8, in which an antifriction roller 10 is journaled.

12 designates a resilient clamp fixed at one end to the bed-plate 2 by suitable means such, for instance, as a screw or rivet 14 and extending upwardly and forwardly towards the gage 4, its forward end 13 being turned upwardly to press against one end of the blade B to firmly hold the same against the inclined surfaces 6 of said gage 4.

The resilient clamp 12 is drawn firmly into engagement with the blade B by a screw 18 extending downwardly through an opening in the bed-plate 2 and provided with a thumb-nut 20 whereby it is adjusted.

The cutting edge C of the blade B is held in parallel relation to the roller 10 through 55 the intermediacy of set screws 21 and 22 threaded in the bed-plate 2, which is reinforced with bosses 24.

The end of the gage 4 adjacent to the handle of the scissors is provided with an abutment 26 against which the blade D is placed preparatory to clamping the blade B in position to be sharpened.

In practice the thumb-nut 20 is loosened to permit the clamp 12 to spring upwardly 60 away from the gage 4, so that either blade of the scissors A can be readily placed

against the inclined surface 6 of said gage 4. The set screws 21 and 22 are then adjusted to bring the cutting edge of the blade B in 70 parallel relation to the roller 10, after which said blade B is firmly clamped against the gage 4 by the clamp 12, which is drawn downwardly against the blade B by turning the thumb-nut 20. A whet-stone, file or 75 other instrument E is then moved back and forth over the roller 10 and the edge of the blade B, which is thereby given the proper bevel and thoroughly sharpened. After one blade has been sharpened the scissors A are 80 reversed to bring the blade D into position to be sharpened.

From the foregoing description it is apparent that we have provided a sharpening device embodying the advantages above 85 pointed out; and while we have shown and described the preferred construction, combination and arrangement of parts we reserve the right to make such changes as properly fall within the spirit and scope of the invention as claimed.

Having thus described our invention, what we claim and desire to secure by Letters Patent, is:

1. A scissors sharpener consisting of a 95 bed-plate having a gage at its rear portion, clamp means for holding either blade of a pair of scissors against said gage, an abutment on the gage against which one blade of the scissors bears while the other blade is 100 being sharpened, an antifriction roller at the forward portion of the bed-plate, and set screws for adjusting the blades in parallel relation with said roller preparatory to sharpening said blades.

2. In a scissors sharpener, a bed-plate,

means for securing either blade of a pair of scissors in position upon said bed-plate, a sharpener guide mounted on the bed-plate, and two elements spaced apart and threaded in said bed-plate to adjust the secured end of either blade up or down to bring the same in parallel relation with said guide.

In testimony whereof we affix our signatures, in the presence of two witnesses.

THOMAS O. HOPKINS.
SIDNEY H. EASTERDAY.
